PROCESS OF MAKING FOOTWEAR

Application filed October 6, 1928. Serial No. 310,735.

This invention relates to an improvement in shoes or similar footwear which have an upper, and an insole, all made of cloth, and are formed by cementing a rubber outsole 5 on to the bottom. According to the present invention, the footwear is provided with two insoles of different sizes, and the margin of the larger insole made of cloth is stitched up to and around the lower circumference of 10 an upper of like cloth properly cut and tailored. The stitched-up edges of the larger insole and the upper are then bent down underneath the larger insole, a depression thus formed in the middle of the insole being fitted 15 up and filled with a smaller insole made of like cloth, after which a welt consisting of a rubber tape is stuck thereto so as to wrap up around the edge of the lower surface of the insole as well as the lower circumference 20 of the upper, while a rubber outsole is stuck over the lower surface of the insole and the welt. The object of the present invention is to prevent the stitched-up edges of the upper and the larger insole from becoming bulky by 25 laying them in the marginal step formed around the insoles differing in size, and to cause the footwear to be comfortable to the wearer by securing the rubber outsole and the welt over the smooth surface in an easy 30 and perfect manner, moreover, giving it durability and strength in every respect.

For a better understanding of my invention, reference is made to the accompanying drawings wherein:

Fig. 1 and Fig. 2 are perspective views of two types of footwear in accordance with the present invention.

Fig. 3 is a vertical section of a partially completed shoe in accordance with the invention,

Fig. 4 is a perspective view of an insole in accordance with the invention.

Same figures used on the drawings show the same or the like parts.

Considering the invention more in detail in connection with the drawings, an upper (1) is suitably cut and tailored into a proper shape out of such textiles as made of cotton, hemp, wool, and/or other fibrous materials.

The margin of the larger insole (2) made of

like cloth is stitched up with stitching yarn (3) to and around the lower circumference of the upper (1). The stitched-up edges (4) are then bent down underneath the insole (2), and the depressed space (5) thus formed in the middle of the insole is filled up with a smaller insole (6) made of like cloth, which is either secured with the stitching yarn (7) or cemented into the position with rubber cement, so that the lower part of the upper (1) 55 and the lower surface of the insole (6) are caused to form a common flat surface. Then, by using rubber cement, is stuck thereto a welt (9) consisting of a rubber tape so as to wrap up around the edge of the lower 60 surface of the insole (6) as well as lower circumference of the upper, while a rubber outsole (8) is stuck over the lower surface of the insole (6) and the welt (9), thus forming 65 the footwear.

My invention can of course be applied to footwear in the style of either a shoe or a "tabi". "Tabi" is a type of footwear generally worn by the Japanese, which differ greatly from a shoe in its having a separate 70 part for the great toe.

Not only this, but also the tying of footwear made in accordance with the present invention can be done in whichever convenient manner of tying by means of a shoe-lace (10) 80 passed through the eyelets suitably provided on the upper part of the upper, or of fastening the clasps (11) up to the matching-strings (11') suitably provided on the back of the upper.

In the present invention, as above mentioned, a larger insole (2) and a smaller one (6) both made of cloth are put together one above the other, and the margin of the former is stitched up to and around the lower circumference of the upper (1) made of like cloth. The stitched-up edges are then bent down in such a manner that they become closed in the marginal step formed by the said insoles differing in size, thus causing 95 the lower circumference of the upper (1) and the lower surface of the insole (6) to form a common flat surface, around and over which are stuck the welt (9) and the outsole (8) both made of rubber, whereby is prevented 100

the bulkiness of the stitched-up edges and afforded footwear comfortable to the wearer. At the same time, the working is made easy and perfect through the sticking of rubber welt (9) and outsole (8) over the flat surface, with additional advantages of the entire structure being made strong and durable.

I claim:

10 A method of making footwear, which comprises stitching the marginal portion of a cloth insole to the lower edge of a cloth upper, bending said stitched portion of the insole and upper under said insole, fitting a smaller insole to the under side of said first named insole within the margin formed by the bent stitched portion, bending a rubber tape welt around said bent portion and securing said tape to the under surface of said smaller insole and to said upper, and securing a rubber outer-sole to the lower surface of said smaller insole and to said welt.

20 In testimony whereof I affix my signature.
TAIZO KURATA.
